HAND LAMP

Halvard F. Nygard, Madison, Wis., assignor to
Burgess Battery Company, Freeport, Ill., a cor-
poration of Wisconsin

Original application September 21, 1931, Serial
No. 564,074. Divided and this application July
3, 1934, Serial No. 733,568

2 Claims. (Cl. 240—10.6)

This invention relates to improvements in electric hand lamps and more particularly to improvements in spare bulb holders and hangers for electric hand lamps. This application is a 5 division of my copending application Serial No. 564,074, filed September 21, 1931 now Patent No. 1,986,281, granted January 1, 1935.

In the drawing:

Fig. 1 is a fractional sectional view of a hand 10 lamp showing the improved spare bulb holder and hanger incorporated in the end cap thereof;

Fig. 2 is a bottom plan view of the hand lamp;

Fig. 3 is a top plan view of the end cap;

Fig. 4 is a plan view of the hanger forming a 15 part of the end cap;

Fig. 5 is an end elevation thereof;

Fig. 6 is a sectional view thereof;

Fig. 7 is an end elevation of the spare bulb 20 holder;

Fig. 8 is a bottom plan view thereof;

Fig. 9 is a side elevation thereof;

Fig. 10 is a plan view of a wear plate employed 25 in the end cap; and

Fig. 11 is an end elevation thereof.

25 My improved and simplified hanger is attached to the end of the battery casing and is adapted to snap into both the open and closed positions from a point between the two. The battery casing 10 is of the usual metallic tubular type. It 30 is closed at its lower end by means of an end cap 11 which is threadedly engaged with the lower end of the casing. The end cap contains a coil spring 12 which constantly urges battery 13 toward the upper end of casing 10.

35 The end cap 11 is provided with raised areas 14, 15 and 16. A hanger or garter ring 17 is arranged on the end cap. It is composed of heavy steel wire and has two adjacent inner ends 18 and 19 which pass through lateral holes 40 in opposite sides of raised portion 16. These holes are flush with the depressed surface between raised portions 14, 15 and 16. The ends of hanger 17 form a hinge joint with raised portion 16 and the hanger is adapted to fold into 45 the depressed area so that the hand lamp may stand upright on the end cap. The ends 18 and 19 are bent up sharply, as shown at 20 and 21 (see Figs. 5 and 6). These ends are bent up with reference to the balance of the hanger 17 to 50 cause them to press against the interior surface of raised area 16 when the hanger is about one-third open.

When in this position the portions of ends 18 and 19 passing through the lateral holes in raised 55 area 16 are thrust or pressed upward against

the edges of said holes to provide sufficient frictional contact to hold the hanger in a predetermined position. In addition, this pressure against ends 18 and 19 tends to give a snap to the action of the hanger as it turns past the 5 high points of the bent-up tips 20 and 21. As the hanger 17 moves to a closed position against the depressed portion of end cap 11, there is a tendency for it to snap into such position as the bent-up tips 20 and 21 turn over, these tips 10 acting as cams. However, the hanger does not turn far enough to release this pressure so that there is enough friction between the bent-up tips and the end cap when the hanger is closed to keep it in that position. As the hanger is 15 moved to a completely open position from the part-way position, it snaps open when the bent-up tips 20 and 21 turn over under the pressure supplied by the edges of the lateral holes in raised area 16 against the journaled portions of 20 ends 18 and 19. The hanger 17 is therefore 25 free to move in the open position, that is, when it is at right angles or at a greater angle to the plane of the bottom of end cap 11. Since end cap 11 is usually made of brass or other relatively soft metal which may be drawn, it wears rapidly and is cut where ends 20 and 21 make contact with it. To prevent excessive wear a thin plate 22 (see Figs. 10 and 11) of hardened 30 steel is inserted adjacent the interior surface of raised area 16. This plate has a ridge 23 across the middle of it to prevent the lateral shifting of the ends 18 and 19 and thereby maintain hanger 17 in position.

The end cap 11 is also provided with an improved and simplified spare bulb holder or clip 24 (see Figs. 7, 8 and 9). This is made of a strip of brass or other suitable sheet metal bent in the form of a shallow V. At the center thereof tongues 25 and 26 are punched into the crotch 40 of the V between which a spare bulb 27 may be inserted and held. The holder 24 is inverted and inserted into the interior of the end cap straddling the bottom as shown in Fig. 1. The end cap spring 12 which urges the battery forward is 45 inserted over the holder which it straddles. The bottom convolution of the spiral spring 12 presses against the ends of the legs of the holder 24 adjacent the bottom of the end cap 11 to thereby hold it firmly in place and allow the easy removal 50 thereof when it becomes necessary to remove the bulb therefrom.

I claim:

1. The combination with a hand lamp casing having a closed end, said closed end having lat- 55

eral openings therein and having a substantially rigid flat surface, of a garter ring secured to and adapted to fold against said end, said garter ring having two free ends in end to end relation passing through said openings and being journaled therein, the tips of said free ends being so bent and shaped as to exert resilient pressure against said surface when said garter ring is in a partially opened position whereby said garter ring, when operated, tends to snap into the closed or opened position, and a wear-resisting member interposed between said ends and said surface.

2. The combination of an end cap for a hand lamp casing having an externally projecting portion in the bottom of said end cap, said projecting portion having a substantially rigid flat sur-

face and having lateral openings in two opposite walls thereof, and a garter ring having two free ends in spaced, adjacent, opposed relation, said ends passing through said openings respectively and being journaled therein, said free ends being so shaped as to exert pressure against said substantially rigid flat surface of said projecting portion when said garter ring is in partially opened position, and a combination abutment and wear-resisting member, the abutment portion of said member being disposed between said free ends of said garter ring for maintaining said garter ring in position, the wear-resisting portion of said member being interposed between said free ends and said surface.
